UNITED STATES PATENT OFFICE.

HARRY J. GUYMON, OF SPRINGFIELD, ILLINOIS.

DESIGN FOR A CAR-CHECK HOLDER.

58,227.

Specification for Design.

Patented June 28, 1921.

Application filed July 31, 1920. Serial No. 400,552. Term of patent $3\frac{1}{2}$ years.

To all whom it may concern:

Be it known that I, HARRY J. GUYMON, a citizen of the United States, residing at Springfield, in the county of Sangamon and State of Illinois, have invented a new, original, and ornamental Design for Car-Check Holders, of which the following is a specification, reference being had to the accompanying drawing, forming part thereof.

The figure is a perspective view of a car check holder, showing my new design.

I claim:

The ornamental design for a car-check holder, as shown.

HARRY J. GUYMON.
